INVENTOR

Edward St. J. Phillips

UNITED STATES PATENT OFFICE.

EDWARD ST. JOHN PHILLIPS, OF LONDON, ENGLAND.

STAIR-EYE TO FACILITATE THE LAYING DOWN AND TAKING UP OF STAIR-CARPETS.

1,373,148.

Specification of Letters Patent. Patented Mar. 29, 1921.

Application filed March 20, 1920. Serial No. 367,435.

To all whom it may concern:

Be it known that I, EDWARD ST. JOHN PHILLIPS, a subject of the King of Great Britain and Ireland, residing at London, England, have invented certain new and useful Improvements in Stair-Eyes to Facilitate the Laying Down and Taking Up of Stair-Carpets; and I do hereby declare that the following is a full, clear, and exact 10 description of the invention, such as will enable others skilled in the art to which it appertains to make and use the same.

This invention relates to a new or improved stair eye for securing stair rods and 15 has for its object a simple and effective construction whereby the laying down and taking up of stair carpets and other stair coverings or the like is greatly facilitated.

In stair eyes, as hitherto constructed the 20 eyes are fixed to the stair treads in such a manner that when the carpet or other covering has been placed in position, one end of the rod is inserted into one of the eyes, and the rod moved longitudinally to engage the 25 opposite end with the eye on the opposite side of the tread. In other constructions the eye is hinged to a bracket fixed to the stair tread. These constructions present many disadvantages inasmuch as in the 30 former construction difficulty is often experienced in securing the rod in position while in the latter construction the rods very often become loose and displaced.

According to the present invention the 35 eyes are formed in two parts one of which is formed with or rigidly secured to the bracket fixed to the stair tread while the other is adapted to be slidden with respect to the fixed part. The movable member is adapted 40 to be moved in such a position as to enable the rod to be dropped into position after which the movable member is returned to its normal position.

The arrangement of the eye is such that 45 the carpet or other covering and the stair or other rods are always maintained in their proper position, while when the carpet is taken up the rods may be removed in much less time and with much less labor than 50 hitherto.

In order that the invention may be readily understood reference is made to the accompanying drawings, in which:—

Figure 1 is a transverse section through 55 one of the stair eyes showing the stair rod just about to be dropped into position.

Fig. 2 is a front view of Fig. 1.

Fig. 3 is a side elevation of one of the eyes showing the stair rod in position, and,

Fig. 4 is a plan view of one of the eyes 60 partly in section.

The stair eye comprises a substantially L shaped bracket *a*, the forwardly extending limb *a*¹ of which is provided with a point or spiked member *b*, adapted to be forced 65 into the tread *c* of the stair.

Its forward end is extended upwardly at *d*, the inner surface of which constitutes the fixed portion of the stair eye, and is curved as shown so that the stair rod *e* snugly fits 70 therein. The rear vertical portion *a*² of the bracket is provided with a central vertical slot *f* at the back of which is an enlarged recess *f*¹. The upper end of the rear portion *a*² is also provided with a hole or perforation to receive an ordinary wood screw 75 *g* by means of which the bracket is securely held in position.

The movable part of the stair eye comprises a curved wedge shaped member *h*, 80 the rear face of which is provided with an enlarged head *k* adapted to slidably fit into the recess *f*¹ while the head is connected to the wedge shaped member *h* by a reduced neck *k*¹ adapted to form a sliding fit in the 85 vertical slot *f* of the bracket. The upper surface of the member *h* is provided with a knob or button *m*, to facilitate its operation.

The operation will be readily understood.

The stair eye is fitted in the desired position by first forcing the point or spiked member *b* into the stair tread and afterward inserting the screw *g*. After the stair carpet or other covering has been laid, the movable wedge shaped members *h* of each 95 stair eye are raised to the position shown in Figs. 1 and 2 and the stair rod *e* is inserted between it and the fixed member *d*. The stair rod now drops into position behind and in engagement with the inner curved surface of the part *d*. The movable member *h* of the stair eye is now dropped or moved 100 downwardly to the position shown in Fig. 3, and the rod is firmly and securely held in position.

What I claim as my invention and desire to secure by Letters Patent in the United States of America is:—

1. An eye for stair and the like rods, comprising in combination, a substantially L 110 shaped bracket, a fixed member projecting upwardly from the front thereof and shaped

on its inner side to receive the stair rod, a vertical slot in the rear portion of said bracket, a slidabile member adapted to be moved vertically in said slot, said slidabile member having a curved inner surface co-operating with said fixed member to engage said stair rod on opposite sides for the purposes set forth.

2. In an eye for stair and the like rods, 10 the combination of a substantially L shaped bracket, a fixed member projecting upwardly from the front thereof and shaped on its inner side to embrace the stair rod, a vertical slot in the rear portion of said bracket, a slidabile member adapted to be moved vertically, in said slot, a movable member adapted to be slidden vertically in said slot, said movable member being shaped on its forward surface to partly embrace the 20 stair rod, and to coöperate with the fixed member of the bracket to hold the stair rod in position, for the purposes described.

3. In an eye for stair and the like rods the combination of a substantially L shaped 25 bracket, a fixed member projecting up-

wardly from the front thereof and shaped on its inner side to receive the stair rod, a vertical slot in the rear portion of said bracket, an enlarged recess at the back of said slot, a slidabile member formed with 30 an enlarged head or button adapted to engage in said slot and recess and provided with a suitably shaped forward surface to coöperate with the fixed member of said bracket to form the eye for the rod. 35

4. In an eye for stair and the like rods, the combination of a substantially L shaped bracket, a fixed member projecting upwardly from the front thereof and shaped on its inner side to receive the stair rod, a vertical slot in the rear portion of said bracket, a recess at the back of said slot, a wedge shaped slidabile member formed with a T shaped projection adapted to slide in said slot and recess and having its front surface 40 shaped to coöperate with the fixed member to form the eye for the stair rod, for the purposes described. 45

In witness whereof I affix my signature.
EDWARD ST. JOHN PHILLIPS.
